ATTORNEY.

UNITED STATES PATENT OFFICE

1,922,218

MONUMENT

George Ritter, Pinckneyville, Ill.

Original application June 23, 1930, Serial No. 463,109. Divided and this application January 19, 1931. Serial No. 509,619

1 Claim. (Cl. 72—7.2)

- My invention has relation to improvements in monuments and it consists in the novel features of construction more fully set forth in the specification and pointed out in the claim.
- 5 The subject matter of the present invention has been divided out of my co-pending application on Concrete monuments and methods of manufacturing the same, filed June 23, 1930, under Ser. No. 463,109.
- 10 The principal object of the present invention is the building of monuments for grave markers, and equivalent purposes, of concrete sections assembled into a closely knit structure very nearly resembling the customary monolithic block. The 15 concrete monument made according to my invention can be manufactured at approximately one-third of the cost of a cut stone of high quality and is equally as durable. The advantage of building the monument in sections 20 is that the sides and ends of the monument may be molded face downward and the cement troweled sufficiently to expel excess moisture, thus obtaining a product of greater density than could be obtained if the entire monument were molded 25 as a single unit. A further object of individually molding the slabs that constitute the sides of the monument is that suitable dies may be employed in the mold for casting any suitable inscription in the slab.
- 30 My invention also contemplates molding the slabs with a suitable recess instead of an inscription, and molding separately an inscribed plate which is adapted for insertion into the recess of the slab. I am thereby enabled to 35 make up a suitable stock of monument slabs in advance, providing the inscribed plates as needed. These advantages, together with others, inherent in the invention will be better apparent from a detailed description thereof in connection 40 with the accompanying drawing in which:
- Figure 1 is a perspective view of a monument made according to my improved method; Fig. 2 is a vertical cross-section taken through the monument on line 2—2 of Fig. 1; Fig. 3 is a 45 horizontal cross-section through the monument taken on the line 3—3 of Fig. 1; and Fig. 4 is a perspective view of a name plate with the name cast in it.
- Referring to the drawing, 1 represents a concrete slab that forms the sub-base of the monument, 2 is the molded base resting thereon and cemented thereto as shown by the joint 3. Slabs 4 and 5 form the rear and front walls of the hollow monument and slabs 6 and 7 form the 55 end walls thereof, which end walls are recessed at the inner corners as shown at e, e to receive the ends of slabs 4 and 5 cemented therein. A cap 8 of any desired shape is set on the upper edges of the side and end slabs and cemented to said slabs as shown by the joints 9. The 60 slabs 4, 5, 6, and 7 are set upon the base 2 and cemented thereto as indicated by the joints 10. The joints 3, 9, and 10, as well as those in the recesses e, are preferably tooled in such a manner as to give the appearance of cut 65 stone.
- In molding the slabs 4, 5, 6, and 7, eyes, or staples, 11 may be placed in them (as shown Fig. 3) and after the sides have been erected, and before cap 8 is in place, a wire 12 may be 70 stretched between the eyes in the slabs 6 and 7, and wires 13, 13 may be stretched between opposite eyes in slabs 4 and 5; weights 14, 15, 15 may be hung from the respective wires so as to exert an inwardly acting force on the slabs, 75 thereby holding them firmly together during the period that the cement is soft. Pressure may be temporarily employed from the outside of the slabs while the cement is hardening in lieu of the weights within. In molding the front 80 slab 5 a recess 16 is formed in it and a name plate 17 is set into said recess and cemented therein, tooled joints 18 being formed around the plate 17 to give the appearance of a cut border. The inscription 19 on the plate 17 is 85 cast into said plate in a manner described in my co-pending application above referred to.
- Having described my invention I claim:
- A monument comprising a suitable base, individual slabs erected on said base to form the 90 sides of the monument, said slabs being in abutting relation at the corners of the monument, a suitable cap disposed on the sides, tie members connecting opposite sides, and a weight connected with the tie members and suspended therefrom for exerting tension inwardly on said 95 tying members.

GEORGE RITTER.
